HUMIDOR CIGAR CASE

Alpha W. Stephenson, Grand Rapids, Mich., assignor to The E. O. Bulman Manufacturing Company, Inc., Grand Rapids, Mich., a corporation of Michigan

Application October 4, 1951, Serial No. 249,770

3 Claims. (Cl. 312—31)

1

This invention relates to a humidified self-service cigar case. It is particularly intended to display boxed cigars in a conspicuous manner so that they may be selected by the customer without the help of a clerk, and the case also provides storage space for a reserve stock of cigars and tobacco, both the reserve stock and the cigars on display being constantly humidified by a controlled flow of moist air which flows under pressure through the stock chambers and thence over the displayed cigars, and a part of the moist air, combined with fresh air from the exterior of the case, is returned into the case where it is rehumidified and continually passes over and around the reserve and display stock, keeping them in proper fresh and moist condition.

The device is provided with various novel features of construction and arrangement as hereinafter particularly described, reference being had to the accompanying drawings in which:

Fig. 1 is a front perspective view of a case embodying the invention.

Fig. 2 is a longitudinal sectional elevation on the line 2—2 of Fig. 3.

Fig. 3 is a transverse sectional elevation on the line 3—3 of Fig. 2.

Fig. 4 is a fragmentary plan view of the humidifying chamber showing the air flow control valve, and

Fig. 5 is an elevation, partly in section on the line 5—5 of Fig. 3, of the humidifying chamber.

Like reference numerals apply to like parts in all of the figures.

The display case is mounted on a suitable base 1 which forms no part of the invention. The case has ends 2, a bottom 3, a top 4, and an intermediate shelf 5 which divides the interior of the case into upper and lower compartments 6 and 7. The back of the case is closed by conventional sliding doors 8 which fit quite closely to provide adequate air seal.

Within the lower compartment 7 is located the humidifying chamber which comprises a box 9 having a removable top 10. The interior of the box is divided into two chambers 11 and 12. The chamber 11 has an air inlet opening 13 and contains a blower fan 14, which has a delivery outlet 14^a into the chamber 12. The fan is provided with suitable driving means such as a small electric motor (not shown).

The chamber 12 contains the humidifying device which comprises a water container 15 open at its top, and preferably made of glass or a plastic material which will resist lime deposit and cor-

2

rosion. A series of horizontal bars 16 extend across the container 15 near its top, and fabric wicking or suitable absorptive material 17 is draped over the rods 16 and hangs down between the rods into water in the container. A float 18 is mounted on an arm 19 pivoted to a side of the box 9, and an upwardly extending rod 20 on the arm 19 extends through an opening in the top 10 of the box. The float rests upon the water in the container 15 and rises or lowers with its level and indicates by the rod 20 the amount of water in the container. The rod 20 may be calibrated for this purpose. The chamber 12 is provided with a plurality of outlet openings 12^a near its top and also with a controllable air outlet which consists of a plurality of openings 21 in the cover 10, and a plate 22 having similar openings 23 is slidably mounted over the cover and may be moved so that its openings 23 are either in full register or partial register with the openings 22 in the cover, thereby providing means for controlling the amount of humidified air emitted from the humidifier into the cigar case.

The stock compartments 6 and 7 are partially closed at their fronts by vertical walls 25 and 26, which extend upwardly from the compartment bottoms 3 and 5 nearly to the tops of the compartments. Small spaces or gaps 25^a and 26^a are left along the upper edges of the walls 25 and 26, and the upper edges are beveled inwardly, which provide restricted funnel-shaped air outlets from the compartments 6 and 7 at their top front corners. The front wall 26 for the lower compartment 7 is provided at its lower edge with an opening 26^b which serves as a return air inlet which communicates with the inlet opening into the fan chamber 13 of the humidifier. Air passages 27 are provided in the bottom of the compartment 6.

The forward portions of the shelves 3 and 5 in front of the vertical walls 25 and 26 serve as supports for cigar boxes. Molding strips 28 are preferably attached to the front edges of these shelves and extend slightly above them and serve as stops against which the forward edges of the cigar boxes on display may be aligned. These shelves forward of the walls 25 and 26 are somewhat wider than the widths of the cigar boxes, and when resting on the shelves with their fronts aligned against the moldings 28 the cigar box lids, which are hinged to the rear of the boxes, are opened and lean in an inclined position against the vertical walls 25 and 26, leaving air circulation spaces between the cigar boxes and their lids and the said vertical walls.

3

Deflecting plates 30 of glass or other suitable transparent material, extend downwardly at an angle from the forward edges of the top 4 and shelf 5, being spaced forwardly from the vertical walls 25 and 26 and having the upper edges of the cigar box lids located behind them. These plates 30 deflect the air emitted from the passageways 25^a and 26^a in a downward direction so that it will flow over and into the cigar boxes and cigars within them.

A humidity controlled electric switch of conventional design is provided in a box 35 within the compartment 7 where it is exposed to the air therein, and this switch is wired into the electric circuit for the motor which drives the blower 14 and acts to automatically stop or start operation of the blower in accordance with the humidity of the air in the chamber.

Operation

Boxes of cigars are placed on the forward parts of the shelves 3 and 5, their fronts aligned against the moldings 28 and their lids inclined rearwardly against the walls 25 and 26 with their upper portions behind the transparent deflector plates 30. The reserve stock of cigars and tobacco is placed within the compartments 6 and 7 but spaced therein to provide air circulation space around them. The water container 15 is provided with the desired amount of water, the fan 14 set in motion and the rear doors 8 are closed.

Air from the exterior entering the case through the passage 26^b is drawn into the chamber 11 of the humidifier box 9 through the opening 13 by the fan 14, which forces it into the chamber 12 where it picks up moisture from the wicking 17. This moist air is then expelled from the box through the outlet opening 12^a and the valved outlet openings 21 and 23 into the compartment 7 from which part of it finds its way into the compartment 6 through the passage 27.

After circulating amongst and conditioning the stock in these compartments, the humidified air, still under pressure from the fan, passes out of the compartments 6 and 7 which have become plenum chambers in which the air in all parts of them is under substantially uniform pressure. Under this uniform pressure the moist air flows out of the passages 25^a and 26^a equally throughout their entire lengths and then is directed downwardly by the deflector plates 30 onto the cigar boxes and their contents, and finds its way into the boxes and around and behind them through the spaces between the boxes as they do not fit tightly against each other. The moist air being relatively heavy, drops by gravity and after circulating around the cigar boxes some of it will pass away from the case, but a part of it which still maintains some of its moisture will be returned, mixed with fresh air from the exterior of the case, through the passage 26^b from where the process of rehumidifying and circulation is repeated.

The extent of humidification can be controlled

4

both by adjusting the valve plate 22 to control the volume of air emitted into the compartments and by varying the amount or depth of water in the container 15, as indicated by the gauge rod 5 20. Also, the humidity controlled switch in the box 35 acts to automatically control operation of the fan in accordance with the degree of humidity within the compartments.

This device serves to maintain both the displayed cigars and the reserve stock in proper moist condition, and distributes the moist air uniformly amongst the reserve stock in the case and also over and around the cigars in the boxes on display.

15 The case provides an open display of cigars within easy reach where the customer can make his own selection without waiting several minutes for clerk service. It takes the customer only a few seconds to select his cigars and hand the pay to the clerk, there being practically no loss of time for the customer or the clerk.

20 The deflector plates 30 of transparent material serve not only their usefulness in deflecting the air downwardly over the cigars, but do not obscure the box lids on which the manufacturers' display appears, and also add a touch of glitter to the general appearance of the display.

25 The invention is defined in the appended claims and is to be considered comprehensive of all forms of construction coming within their scope.

I claim:

1. A humidor cigar case comprising a cabinet having a substantially closed interior, a substantially horizontal shelf on the exterior of the cabinet, a substantially vertical back for said shelf, said back being a wall of said cabinet, means for humidifying air and injecting it under pressure into the interior of the cabinet, an outlet passage from said interior through said back wall in the upper region thereof above said shelf and a downwardly extending deflector plate in front of said outlet passage and spaced from said back and above said shelf, whereby a box of cigars may be supported on said shelf below said deflector with its open cover leaning against said back and behind said deflector.

2. The elements of claim 1 in which said deflector is transparent.

3. The elements of claim 1 in which there are 50 a plurality of said shelves in stepped relation to each other, each having a said back wall, outlet passage and deflector plate whereby humidified air ejected through said outlet passages will cascade downwardly from shelf to shelf and over the cigars in the boxes thereon.

ALPHA W. STEPHENSON.
